BURNER CONTROL SYSTEM

Vilynn O. Beam, Cleveland Heights, Ohio, assignor to The Bryant Heater Company, Cleveland, Ohio, a corporation of Ohio

Original application June 20, 1936, Serial No. 86,381. Divided and this application May 27, 1937, Serial No. 145,087

1 Claim. (Cl. 158—28)

This invention relates to a burner control system and is a division of my copending application Serial No. 86,381, filed June 20, 1936, for Control for fuel burning apparatus. 5 The present invention has particular reference to gas or other fuel burning equipment, including a main burner, a pilot burner, an igniter for the pilot, and a thermal element associated therewith, the principal object of the present invention being to provide a simple, reliable, and efficient control system by which the thermal element controls the supply of gas to the burner or the energization of the igniter, depending upon whether the pilot flame is burning or extinguished 10 and therefore whether the thermal element is hot or cold.

In accordance with the present invention, the thermal element operates suitable switching means which renders effective either the control 20 circuit for the valve or the energizing circuit for the igniter, and when one circuit is rendered effective the other is inoperative so that the valve cannot be opened unless there is a flame at the pilot burner and so that the igniter circuit cannot be completed when the pilot is burning. In the preferred embodiment of the invention, the switching means is a double-throw switch so arranged with respect to the actuating member which is connected to the thermal element as to 25 render either circuit effective and at the same time render the other circuit ineffective.

The invention may be further briefly summarized as consisting in certain novel combinations and arrangements of parts which will be 30 described in the specification and set forth in the appended claim.

In the accompanying sheet of drawings,

Fig. 1 is a view partly in elevation and partly in section showing as much of the gas control 35 system as is material to the invention;

Fig. 2 is a diagrammatic view showing the electric circuits; and

Fig. 3 is a fragmentary detail view showing how the middle contact of a three-pole switch, which 40 is preferably employed with the thermal element, is actuated when the thermal element is heated.

Referring now to the drawing, 10 represents the main burner to which gas will be supplied from the supply pipe 10a in which will be located 45 the main gas valve 10b (see Fig. 2). Any suitable type of main valve may be employed, such, for example, as a commonly employed diaphragm valve which is opened and closed by the supplying of gas pressure to and the exhausting of gas 50 pressures from the chamber above the diaphragm.

through the action of an auxiliary solenoid-type valve. A valve which is controlled or actuated by a solenoid is contemplated in the diagrammatic view of Fig. 2. I wish it to be understood, however, that the present invention, although 5 useful in connection with gas-fired boilers, furnaces, heaters, and the like, is not necessarily confined thereto and when used in connection with gas-fired equipment of this type any suitable type of main valve may be utilized.

In igniting relation to the main burner is a pilot 11 which, as well as the thermal element to be referred to presently, forms a part of a unit having a tubular casing 12 which may be rectangularly or otherwise shaped in cross-section, this casing having a horizontal main portion and at its inner end an upright or vertical portion 12a. Gas is supplied to the pilot 11 by a pipe 13 extending through the horizontal portion of the casing, the pipe 13 being connected 20 to the pilot 11 in a manner such that there will be supplied to the latter a suitable mixture of air and gas. The pilot 11 extends up from the horizontal portion of the casing 12 in front of the upright portion 12a thereof and is steadied 25 by the flange of a bracket 14 secured to the upper part of the vertical portion 12a of the casing. If a main valve of the diaphragm type is utilized, a bleed pipe is employed to carry the gas from the upper chamber of the valve when the latter 30 is to be opened by gas pressure beneath the diaphragm, and in that case the bleed pipe may also extend through the casing 12 alongside the pilot pipe 13 and it may have a vertical extension alongside the pilot 11 but will terminate short 35 of the upper end thereof. However, this bleed pipe forms no part of the present invention and will not be further referred to.

The thermal element per se forms no part of the present invention as it is claimed in my pending application referred to. The present invention is not limited to the particular construction of thermal element therein shown and claimed but is preferred and is therefore illustrated in the drawing of the present application. It will 40 be observed that this element 16 is composed of two members 16a and 16b which are pivotally connected by cross-pins 16c to the upper part of the vertical portion 12a of the casing 12 and project outwardly and upwardly therefrom. At 45 their upper ends these members are pivotally connected together by a pivot pin 16a. The member 16a is next to the pilot 11, and this member which, when compared with the member 16b, is relatively short may be termed the "hot" mem- 50 55

ber of the thermal element. The other member 16b of the thermal element is relatively remote from and shielded from the pilot flame by the hot member 16a and may be termed the "cold" 5 member of the element. This member is relatively long and is in the form of a lever which extends down beyond its pivot pin 16c and at its lower end is connected to the gas controlling element which it is to operate. From their pivot 10 pins 16c to the upper common pivot pin 16d the two members 16a and 16b are normally of equal length, the axes of the three pivot pins forming the corners of an acute isosceles triangle when the element is cold. Though the major portion of the member 16a and the major portion of the upper part of the member 16b are parallel or substantially parallel, their upper ends are in this instance curved inwardly and placed in overlapping relation so that they can be conveniently connected together by the pivot pin 16d. As will appear presently, the heat differential between the member 16a and the upper portion of the member 16b causes the member 16a to expand linearly, and the two fixed pivot points 16c, together with the fact that the members are pivotally coupled together at their ends, compel the relatively hot member to rock on its pivot 25 16c (to the right as the same is viewed in Fig. 1), thus imparting a similar rocking movement to the member 16b which thus acts as a lever to transmit at its lower end to the part to be actuated a movement the extent of which can be made anything desired by the appropriate selection of the ratio of the lengths of the two lever 30 arms above and below the pivot 16c.

In this instance, the lower end of the lever member 16b is connected to a rod 17 which extends horizontally and forwardly through the lower part of the horizontal portion of the casing 12, and operates a double-throw switch 18 located within a switch box 18a secured to the casing 12 and consisting in this case of a movable switch member 18b which is formed of a suitable insulating material and is secured to the rod 17, 45 and three switch blades or contacts 18c, 18d, and 18e which at their outer ends are suitably attached by screws 18f to the top of the switch box 18a and near their free ends are provided with contact points 18g. The middle contact 18d extends outwardly beyond the other two and is adapted to be engaged by the movable switch member 18b. Normally or when the thermostat is cold, the switch contact 18d engages the lower contact 18c, as shown in Fig. 1, and when the 50 thermal element is heated and functions in the manner pointed out above, it moves the middle contact into engagement with the upper contact 18e, as shown in Fig. 3.

By reference to Fig. 1, it will be seen that the 55 pilot has a lower orifice 11a for the emission of gas to produce the flame F (shown by dotted lines in Fig. 1), which heats the adjacent member 16a of the thermal element, and an upper orifice 11b for the emission of gas for the flame F', also 60 shown by dotted lines in Fig. 1, for igniting the main burner or burners, these two orifices being connected by a spiral slot 11c so that when the gas is ignited at the lower orifice 11a it will travel up the slot and ignite the gas at the upper orifice 65 11b.

It is desirable that the pilot be lit by a suitable 70 ignited generally electrically actuated, and while different forms of igniters may be employed, I prefer to use an igniter of the hot wire type generally in the form of a coil which on the passage

of current therethrough becomes incandescent and therefore sufficiently hot to ignite the gas surrounding it. To accomplish this desirable result, I mount on top of the vertical portion 12a of the casing 12 at the side of the two members of the thermal element a block 19 of heat-resistant material having a channel 19a extending horizontally therethrough, this channel being located alongside and facing the members of the thermal element and projecting inwardly beyond 10 the same toward the pilot 11, the inner end of the channel being located adjacent the lower orifice 11a of the pilot 11. In this channel is placed the igniter coil 20 held in place by terminal screws 20a to which current supplying conductors may be connected.

This device functions as follows: The parts are so related that the gas emerging from the lower orifice 11a of the pilot envelops the coil 20, and when current is passed through the coil and the latter becomes incandescent, it ignites this gas and therefore starts flames at the pilot orifices, but as soon as the flame F is established it is caused by convection to curl upwardly into the channel of the hot member 16a of the thermal 25 element and no longer impinges upon the igniter coil so that its life is substantially unaffected by the heat of the flame.

In Fig. 2 I have shown an electric circuit by which the parts heretofore described may be utilized very effectively, the electric circuit or system herein illustrated being simple, reliable, and involving a maximum degree of safety in the respect that it is impossible for the main valve to be opened to permit the flow of gas to the main burner or burners unless the pilot is burning and the thermal element heated, and in the further respect that the electric circuit cannot be completed through the igniter coil unless the pilot is out and the thermal element is cold. For operating the system, the ordinary house lighting circuit may be utilized the conductors of which circuit are designated 21. The voltage is stepped down to a suitable safe voltage by a transformer 22 composed of a primary 22a and a secondary 45 22b. One terminal of the secondary is connected by a conductor 23 to one terminal or contact 24a of a room thermostat 24, the other terminal of which is connected by a conductor 25 to one terminal of a solenoid 26 which actuates or causes 50 the actuation of the main gas valve 10b supplying current to the main burner or burners. When a diaphragm valve is used, this solenoid actuates an auxiliary valve which controls the supplying of gas pressure to and the exhausting or bleeding 55 of gas pressure from the upper chamber of the diaphragm valve so that the latter may be closed or opened by gas pressure. The other terminal of the solenoid coil is connected by a conductor 27 to the upper contact 18e of the double-throw 60 switch 18 adapted to be operated by the thermal element, as previously described. The lower contact 18c of this switch is connected by conductor 28 to one terminal of the igniter coil 20, the other terminal of which is connected by a conductor 28a 65 to one terminal of a manually operated single-throw switch 29 which is preferably of the push-button type, the other terminal of the switch being connected by conductor 30 to the conductor 23 leading to one terminal of the secondary 22b 70 of the transformer. The other terminal of the secondary of the transformer is connected by a conductor 31 to the middle contact 18d of the switch 18 which contact is adapted to be actuated or moved from the position shown in Fig. 1 to the

position shown in Fig. 3 by the movable switch member 18b which is shifted by the thermal element.

Assuming that the main gas valve is closed and that the pilot is extinguished, in which event the thermal element is of course cold, the parts of the thermal element are in the position shown in Fig. 1 and the middle contact 18d of the double-throw switch 18 engages the lower contact 18c. This establishes two conditions—it keeps the circuit through the solenoid 26 open, making it impossible for the main gas valve to be actuated even though the room thermostat calls for heat, and, at the same time, the engagement of the middle contact 18d of the switch 18 with the lower contact 18c makes it possible to energize the igniter coil 20 by closing the switch 29, attention again being called to the fact that the circuit through the ignited coil cannot be closed if the pilot is burning and the thermal element heated.

Accordingly, when the operator desires to start the furnace of other fuel-consuming apparatus, he has simply to close the switch 29 which will very shortly cause the pilot to be ignited. As soon as the pilot is ignited, the flame F rises and instantly after the ignition occurs the flame is out of contact with the igniter coil.

The flame now plays on the hot member 16a of the thermal element, and while the cold member 16b remains relatively cool, the hot member expands and lengthens, changing the distance between its pivot 16c and the upper pivot 16d which pivotally connects the upper ends of the thermal members. As the hot member 16a gradually lengthens, it transmits lateral thrust to the upper end of the cold member 16b, causing the pivot pin 16d to move in a clockwise direction as the same is viewed in Fig. 1 so that both members rock in a clockwise direction about their respective pivots 16c and move the switch actuating rod 17 to the left as the same is viewed in Fig. 1. The movement imparted directly by the long arm or member of the thermal element to the switch member 18b is sufficient to move the middle contact 18d from the position shown in Fig. 1, i. e., in engagement with the lower contact 18c, into engagement with the upper contact 18e, as shown in Fig. 3. It might be stated at this point that the time element of this part of the cycle can be varied by adjusting the positions of the two contacts 18e and 18c with reference to the middle contact 18d. This can be done by means of an adjusting screw 18h which extends through the top of the switch box 18a and engages the upper contact 18e. This contact is connected with the lower contact 18c by an insulating spacer 18j which passes freely through an opening in the middle contact 18d so that by adjusting the screw the two contacts 18e and 18c can be raised or lowered with reference to the middle contact 18d.

The forward end of the rod 17 is reduced and passes through a suitable support at the front of the switch box. A spring 17a surrounding the reduced end of the rod 17 is compressed when

the thermal element acts in the manner just explained on being heated, but when the pilot is extinguished and the thermal members are cool or reach equal temperature, the parts are restored to their former positions shown in Fig. 1, the spring 17a assisting this action.

When the thermal element is actuated by the pilot flame in the manner just explained so as to bring the middle contact 18d into engagement with the upper contact 18e of the switch 18, the circuit may be completed through the coil of the solenoid 26 which, as previously pointed out, controls the supply of gas to the main burner, and the solenoid will be energized whenever the room thermostat calls for heat, and completes the circuit at the contact 24a. The middle contact of the switch 18 remains in the position just stated so long as the pilot flame is burning and the thermal element is heated, and, accordingly, the main valve will be opened and closed in accordance with the functioning of the room thermostat. Of course, if the equipment is used in a system not involving a room thermostat, the main gas valve can be controlled, i. e., caused to open and close, by other means, such as a manually operable switch which would replace in function the switch automatically operated by the room thermostat.

It should be noted also that, during the entire period that the thermal element is heated by the pilot flame, not only is the switch 18 maintained in a condition such that the main gas valve can be operated whenever desired or as required by temperature conditions in the vicinity of the room thermostat, but, during this period, it is impossible to complete the circuit through the igniter coil.

While I have shown the preferred embodiment of the present invention, I do not desire to be confined to the details or specific members described above, as the principle of the invention may be otherwise utilized, and I therefore aim in my claim to cover all modifications which do not involve a departure from the spirit and scope of the invention in its broadest aspects.

Having thus described my invention, I claim:

In fuel burning equipment, a main burner, a normally continuous pilot therefor, an igniter for the pilot, a thermal element adjacent the pilot in heat transferring relation thereto, a valve for supplying fuel to the burner, an actuating or controlling member therefor, a source of current, a circuit for said member, a circuit for the igniter, a double-throw switch remote from said thermal element mechanically associated therewith, whereby the changes in the thermal element render either circuit effective, a thermostatically operated switch in the circuit for said valve actuating member and a push button switch in the igniter circuit, said thermostatic and manual switches cooperating with said double-throw switch to complete the circuit through either said member or said igniter depending upon whether or not the thermal element is heated by the pilot.

VILYNN O. BEAM.
